P. K. BASMADJIAN

GROCER'S HELPER

Original Filed June 27, 1924

UNITED STATES PATENT OFFICE.

PAUL K. BASMADJIAN, OF PHILADELPHIA, PENNSYLVANIA.

GROCER'S HELPER.

Application filed June 27, 1924, Serial No. 722,654. Renewed January 22, 1927.

My invention relates to devices for use with packages and cans for lifting them from and placing them upon shelves too high to be reached by hand.

5 A purpose of my invention is to pick up a can at its upper rim between a prong or, most desirably spaced prongs of a downwardly directed and longitudinally movable hook over the rim and an upwardly directed point under the rim.

A further purpose is to adapt a downwardly directed hook in cooperation with an upwardly directed point to take hold of rims of variant widths by having the hook resili- 15ently pressed downward while free to yield to upward pressure.

A further purpose is to adapt a resiliently downwardly pressed and downwardly directed hook cooperating with an upwardly directed point in taking hold of a rim to easy release by having the hook latch out of the way when moved upwardly.

A further purpose is to support the side of a can that is being picked up by its upper rim by means of a pair of lateral wings extending to either side of the pick-up device and spaced preferably adjustably below the pick-up device.

A further purpose is to provide a pointed pick up device for packages permitting point pick-up by piercing the covering of the package with means for picking up a can at its upper rim.

Further purposes will appear in the specification and in the claims.

Of the different forms in which my invention may appear I have chosen for illustration one only, selecting a form however that is at once easy and inexpensive to manufacture, convenient and efficient in operation, and which illustrates particularly well the principles involved.

Figure 1 is a perspective view showing the preferred form as carrying a can.

45 Figure 2 is a perspective view of the same form supporting a paste-board box.

Figure 3 is a fragmentary longitudinal section to enlarged scale showing the operative structure.

50 Figure 4 is a fragmentary front elevation at right angles to the view of Figure 3 and with the casing sectioned upon the line 4-4 of Figure 5.

Figure 5 is a section of Figure 4 taken upon 55 the line 5-5,

Figure 6 is a fragmentary perspective showing the hook member latched open.

Similar numerals indicate like parts in all figures.

Describing in illustration and not in limita- 60 tion and referring to the drawings:—

The device as illustrated in its preferred form comprises a handle 10 of suitable length to reach high shelves and carrying at its upper end cooperating hook and needle or other 65 sharpened prong pick up mechanism 11 and 12 respectively, for taking hold of the upper rim 13 of any can. It shows a separate needle 14 for pasteboard packages and lateral supporting wings 15.

70 The hook 11 fits over the rim 13 above the point of the needle 12 and rests against the inner surface 13' of the rim, holding the needle laterally against slipping out so as to pass the flange of the can top. It preferably 75 extends to both sides of the needle, so as to balance the lateral retaining stress, a finger 16 engaging the rim to one side of the needle and a similar finger 17 engaging the rim at the other side thereof. In some cases the 80 needle point will fit in beneath the flange of the can top and in others merely press against the side of the can and against the under edge of the flange, being held to duty here, resili- 85ently where the needle is designed to yield laterally, by the hold of the finger or fingers of the hook.

The hook member is normally resiliently pulled downwardly, as by its own weight but preferably by any suitable spring 18, resting 90 in its unengaged position against a stop 19.

In taking hold of the flange of a can, the hook member is placed over the rim and the handle is pulled downwardly to relatively lift the hook with respect to the needle point, 95 giving sufficient spacing between them so that the hook slides over the rim and laterally engages the inner surface at 13'. The handle is then lifted bringing the needle against the under edge of the upper flange 100 and, with continued lifting, raising the can from the shelf so that it may be taken down.

Spaced somewhat below the hook and point members 11 and 12 I provide lateral supporting wings 15 to engage the side of the can beneath the rim. While not essential these wings add to the convenience and sureness of properly taking hold of the can as they prevent swaying of the can. They are desirably adjustable along the handle so as to 105 110

operate to the best advantage upon cans of different height and are conveniently mounted upon a friction collar 21 which fits the handle snugly enough to stay in place until 5 positively moved.

I find that adaptation of the hook to stay open when fully extended makes release of the rim of the can easier when a can is being placed upon a shelf, and I therefore provide 10 means for holding the hook member open out of the way of the rim for easy release after the can has been placed upon the shelf. This is put in operation by pulling the handle 10 down to extend the hook member.

15 I illustrate in Figures 3 and 4 one means for holding the hook extended. A short pin 22 projects somewhat into the runway 23 of the strip 24 upon which the hook is supported. This pin is so placed with respect to a 20 suitable rearwardly directed shoulder of the strip 24 (such as at the upper edge of a hole 25 through the lower end of the strip) that this shoulder passes and latches back of the pin at an extended position of the hook, holding the hook from automatic return. The 25 latch is released by a slight inward pressure upon the upper end of the hook member.

In the structure of Figures 3 and 4, the upper end of the wooden handle 10 is channeled 30 at 23 to receive the strip 24 carrying the hook 11, and the spring 18 is anchored to the handle at 26 and fastened to the lower end of the strip at 27. This channel 23 forms a longitudinal guideway for the hook member.

35 The needle members 12 and 14 are provided at their lower ends with right-bend pointed shanks 28 and the upper end of the handle, reduced in diameter at 29, is grooved longitudinally to seat these needles members, the 40 shanks 28 being driven radially into the handle.

While I have shown the handle of circular section for convenience in illustration, as a 45 standard or more usual form I have used a square section and could use a great variety of preferably polygonal shapes.

The portion 29 of the handle is reduced to receive a ferrule 30 having the same outside shape or section as the unreduced portion of 50 the handle, and this ferrule locks the needle members 12 and 14 to place in their respective grooves and also encloses and guides a part of the strip 24.

A casing sleeve 31 carrying collar 21 supporting the wings 15 is now slipped down over the ferrule 30 to enclose the channel 23 and the operating mechanism of the hook member. This sleeve 31 is preferably made removable and in the illustration is shown as 55 held in place by means of a screw 32 whose head engages opposite sides of a notch 33 in the upper end of the sleeve. Loosening the screw adapts the sleeve to be slid down to uncover the operating mechanism of the hook.

In view of my invention and disclosure variations and modifications to meet individual whim or particular need will doubtless become evident to others skilled in the art and I therefore claim all such in so far as they fall within the reasonable spirit and scope of my invention.

Having thus described my invention, what I claim as new and desire to secure by Letters Patent is:—

1. In a lifter for packages and cans, a handle, a sharply pointed projection from the upper end of the handle adjacent one side thereof, a downwardly directed and upwardly movable hook having hook portions on opposite sides of the point, and means pressing the hook downwardly.

2. In a lifter for packages and cans, a handle, a needle projection from the upper end of the handle adjacent one side thereof, a downwardly directed hook having prongs on either side of the needle and adapted to be moved above the needle, and resilient means pressing the hook downwardly.

3. In a lifter for packages and cans, a handle, a pointed projection at the upper end of the handle and a hook at one side of the projection normally, resiliently drawn toward the projection adapted to engage the inside of the rim of a can above the body of the can and to hold the point of the projection against the side of the can.

4. In a lifter for packages and cans, a handle, a needle projection from the upper end of the handle, a downwardly directed and upwardly movable hook having hook portions spaced on opposite sides of the needle, means pressing the hook downwardly, and means engaging the hook member in its raised position adapted to hold it in raised position.

5. In a lifter for packages and cans, a handle having at its upper end an upwardly directed pointed projection, an upwardly movable hook adapted to engage the inside of the rim of a can above the body of the can to hold the projection against the outside of the can beneath the upper flange of the can, spring means for pulling the hook downwardly and means for holding the movable hook in raised position to release a can which has been lifted by the helper.

6. In a lifter for packages and cans, a handle, a needle projection from the upper end of the handle, a downwardly directed and upwardly movable hook having hook portions spaced on opposite sides of the needle, means pressing the hook downwardly, and a latch operating to hold the hook in raised position after the hook has been raised.

7. In a lifter for packages and cans, a handle, a sharply pointed projection from the upper end of the handle adjacent one side thereof, a downwardly directed and upwardly movable hook above the projection, spring means forcing the hook downwardly and

supporting wings extending from one side of the handle at a point spaced somewhat below the pointed projection.

8. In a lifter for packages and cans, a handle, a pair of circumferentially spaced needle projections adjacent the circumference thereof, a downwardly directed and upwardly movable hook having prongs spaced on opposite sides of one of the needles, and resilient means pressing the hook downwardly.

9. In a lifter for packages and cans, a handle, a needle projection from the upper end thereof, a downwardly directed and upwardly movable hook member somewhat above the needle, supporting wings somewhat below the needle extending to either side thereof from the handle, means pressing the hook downwardly, and means for holding the hook member in raised position operative after the hook has been raised.

10. In a lifter for packages and cans, a handle, an upwardly directed pointed member at the upper end of the handle at the side, a hook adapted to engage the inside of the upper rim of a can and hold the pointed member to its duty, a spring forcing the hook downwardly and wings beneath the hook adapted to steady a can against tilting about the handle.

11. In a lifter for packages and cans, a handle, an upwardly directed pointed member at

the upper end of the handle at the side, a hook adapted to engage the inside of the upper rim of a can and hold the pointed member to its duty, balanced to engage the rim at spaced points with the pointed member between them and wings beneath the hook adapted to steady a can against tilting about the handle.

12. In a lifter for packages and cans, a handle, a needle projection from the upper end thereof, a downwardly directed and upwardly movable hook above the projection, means pressing the hook downwardly, a friction sleeve mounted on the handle beneath the end thereof and adjustable therewith, and supporting wings extending from one side of the sleeve and integral therewith.

13. In a lifter for packages and cans, a handle having a channel from its upper end downwardly, a needle projection from the upper end thereof, a hook member having a supporting strip guided by and sliding in the channel and having a downwardly directed hook portion above the needle, a downwardly directed abutment on the strip in the channel, a projection in the channel normally laterally displacing the strip and at raised position of the hook registering back of the abutment to latch the strip in raised position, and means pulling the strip downwardly.

PAUL K. BASMADJIAN.
